UNITED STATES PATENT OFFICE.

EDWARD L. C. CLARK, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,199,246.

Specification of Letters Patent. Patented Sept. 26, 1916.

Application filed April 9, 1910. Serial No. 554,386.

To all whom it may concern:

Be it known that I, EDWARD L. C. CLARK, a citizen of the United States, residing at Middletown, in the county of Middlesex and State of Connecticut, have invented certain new and useful Improvements in Type-Writing Machines, of which the following is a full, clear, and exact description, such as will enable others skilled in the art to which it appertains to make and use the same.

This invention relates to ribbon mechanism for typewriting machines, and with regard to the more specific features thereof, to means for mounting the ribbon.

One of the objects of the present invention is to provide a device of the above character which will be practical in construction and efficient in operation.

Another object is to provide a device of the above character which will be simple in construction and cheap to manufacture.

A further object is to provide an improved ribbon mounting which will permit the ready attaching and detaching of the ribbon therefrom.

Other objects will be in part obvious and in part hereinafter pointed out.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of many possible embodiments of my invention, Figure 1 is a plan view showing the manner in which the ends of the ribbon are attached to the core and grip, the body part of the ribbon being unwound from both; Fig. 2 is a perspective view of the ribbon core as manufactured; Fig. 3 is a similar view showing the end of the ribbon attached thereto; Fig. 4 is a perspective view of the ribbon grip; Fig. 5 is a plan view of the ribbon reel and grip with the end of the ribbon being inserted therein. Fig. 6 is a detail view of the ribbon reel.

Similar reference characters refer to similar parts throughout the several views of the drawings.

Referring to these drawings in detail, 1

and 2 represent a pair of right and left hand ribbon spools or reels respectively having lower heads or flanges 3 for supporting 55 and guiding a ribbon 4 as it is wound in ribbon cups 5 which, in the embodiment shown, are placed at opposite sides of the machine to feed the ribbon past a printing point 6 under the driving action of any suitable 60 mechanism, not herein shown. These ribbon reels Fig. 6 comprise hollow cylindrical spindles or hubs having a plurality of longitudinally disposed open ended slots 7 adapted to be engaged by a ribbon core 8 65 or grip 9.

The ribbon core 8 on which the ribbon is adapted to be wound and sold therewith in the trade, is stamped from a strip of slightly resilient sheet metal and bent into the form 70 of a hollow cylinder Fig. 2. Both ends are provided with one or more outwardly projecting sharp pointed teeth 10 and a plurality of inwardly projecting elements or lugs 11. The teeth are adapted to engage 75 and pierce one end of the ribbon and be bent downwardly, thereby firmly clamping the ribbon thereto, while the lugs 11 are adapted to engage one of the slots 7 when slipped over either ribbon reel and lock the parts 80 in operative relation whereby they all rotate together to wind the ribbon.

The ribbon grip 9 comprises a strip of resilient material, preferably thin sheet metal bent into the form of a cylinder but 85 having a space 12 between its ends Fig. 4. One end of this strip is provided with a plurality of pointed projections or teeth 13 adapted to engage the free end of the ribbon, as shown in Fig. 5. Slightly to one side 90 of a point diametrically opposite the teeth 13 is provided a longitudinal element or rib 14 adapted to snap into engagement with one of the slots 7 in the ribbon reel when the grip is rotated to lock the same in position 95 against further rotation as in the position shown at the right of Fig. 1. Along the upper edge of the ribbon grip is an inwardly bent ear 15 to facilitate the rotation of the grip within the hub or permit an easy removal therefrom when desired by pressing against the underside of the ear 15. It is thus seen that the end of the ribbon, when the parts are in the position shown in Fig.

5, may be inserted through one of the slots 7 in the reel and between the ends of the grip forming the opening 12 registering therewith, and upon rotating the grip by 5 grasping the ear 15 the teeth 13 will pierce the ribbon and carry it around therewith into the position shown in Fig. 1, in which position the grip co-acts with the reel to firmly clamp the end of the ribbon thereto. 10 The operation and manner of use of this device is substantially as follows: When it is desired to place a new ribbon upon a type-writing machine the core 8 on which the ribbon is wound when purchased is slipped 15 over either of the ribbon reels 1 or 2 allowing the lugs 11 to co-act with one of the slots 7. The free end of the ribbon is then passed through openings 16 in the ribbon cups 5 and the necessary guides and tension 20 members, not shown, past the printing point to the opposite reel, where it is inserted in a similar slot and then through one of the slots 7 in the grip 9 and the grip turned until the flange 14 springs into the slot 7 25 at the opposite side of the reel 1. In this position the ribbon will be firmly clamped in position and the grip locked against further rotation. If desired, the ribbon core may be utilized for fastening the free end 30 of the wound up ribbon, securing it as in Fig. 3 instead of the grip as at the right of Fig. 1 although the present construction is believed to be more advantageous.

It is thus seen that this invention provides for a simple and practical device accomplishing, among others, the objects and advantages above stated, upon which the ribbon may be wound and secured upon the ribbon reel, as well as a co-acting device 40 for securing the free end of the ribbon to the opposite reel to feed the same past the printing point. The pair of ribbon attaching devices, in the present embodiment the core and grip, are interchangeable and of a size and form adapted to fit one within and the other without either reel or spool.

The specific form of the ribbon core herein shown and described is not my invention but forms part of the subject matter of the 50 application of J. A. Ronchetti, filed Apr. 23, 1910, Serial No. 557,127.

As many changes could be made in the above construction and many apparently widely different embodiments of this invention could be made without departing from the scope thereof, it is intended that all matter contained in the above description or shown in the accompanying drawings shall be interpreted as illustrative and not in a 55 limiting sense.

Having described my invention, what I claim as new and desire to secure by Letters Patent, is:

1. In ribbon mechanism, in combination, 60 a ribbon, a rotatable hollow spindle, and a

ribbon grip within said spindle to which one end of the ribbon is adapted to be secured and hold it against the inner wall of said spindle.

2. In ribbon mechanism, in combination, 70 a ribbon, a rotatable hollow support having a slot therein, a ribbon grip adapted to fit within said support and be turned into gripping position, and means adapted to engage said slot to hold the grip against rotation. 75

3. In ribbon mechanism, in combination, 80 a ribbon, a rotatable hollow support having a slot therein, a ribbon grip adapted to fit within said support, and a rib on said grip adapted to engage said slot to lock the grip 85 in position after the ribbon has been secured thereto.

4. In ribbon mechanism, in combination, 85 a ribbon, a rotatable hollow support having slots therein, and a ribbon grip adapted to fit within said support having means adapted to engage one of said slots to lock the grip against rotation after the ribbon has been inserted in another of said slots and secured by said grip. 90

5. In ribbon mechanism, in combination, 95 a ribbon, a rotatable hollow support having slots therein, a ribbon grip having a slot therein adapted to register with one of the slots in said support whereby the end of the ribbon may be inserted within the grip, and means co-acting with the other of said slots on rotation of said grip to lock the grip in fixed position.

6. In ribbon mechanism, in combination, 100 a ribbon, a rotatable hollow support having oppositely disposed slots therein, a cylindrical ribbon grip adapted to fit within said support, said ribbon grip comprising a strip of resilient material bent into a 105 cylindrical form and having a space between the ends thereof adapted to register with one of said slots, and means whereby said ribbon may be firmly clamped to said grip when said slots are moved out of registry. 110

7. In ribbon mechanism, in combination, 115 a ribbon, a rotatable hollow support, said support having oppositely disposed slots, a ribbon grip co-acting with said support comprising a strip of resilient material bent into the form of a cylinder having a space between its ends adapted to register with one of the slots in said support whereby the ribbon may be inserted therein, a 120 rib formed near one end of said grip, and teeth on the opposite end adapted to pierce the ribbon when the grip is rotated.

8. In ribbon mechanism, in combination, 125 a ribbon, a rotatable hollow support, having oppositely disposed slots, a ribbon grip co-acting with said support comprising a strip of resilient material bent into the form of a cylinder having a space between its ends adapted to register with one 130

of the slots in said support whereby the ribbon may be inserted therein, means on said grip adapted to co-act with another of said slots to lock the same against rotation, 5 and means adapted to co-act with said support and firmly hold the end of the ribbon when said grip is rotated.

9. In ribbon mechanism, in combination, a ribbon, a hollow support, having an open 10 end, a grip adapted to co-act with the inside of said support and to hold one end of said ribbon, the means adapted to be pressed to cause removal of said grip from said support through said open end.

15 10. In ribbon mechanism, in combination, a ribbon, a hollow support having an open end, a grip adapted to co-act with the inside of said support to hold one end of said ribbon, and a projecting lug on said 20 grip whereby the same may be grasped to permit ready removal thereof through said open end.

11. An article of manufacture of the character described comprising a strip of 25 resilient material bent into substantially the form of a cylinder and having a space

between its ends, teeth provided at one end of said strip and a projection on its outer cylindrical face intermediate its ends.

12. An article of manufacture of the 30 character described comprising a strip of resilient material bent into substantially the form of a cylinder, an outwardly projecting rib intermediate its ends, one end being provided with projecting points 35 adapted to pierce the end of a ribbon, said strip having an inwardly bent portion along one edge thereof.

13. An attaching device for attaching a ribbon to a spool having a slotted hollow 40 hub, consisting of an internal hub engaging member having means for attaching the ribbon thereto, and projecting means adapted to coact with the spool to prevent relative rotation of the attaching device 45 and the hub.

In testimony whereof I affix my signature in the presence of two witnesses.

EDWARD L. C. CLARK.
